UNITED STATES PATENT OFFICE.

CHARLES A. ROBERTS, OF BUTTE, MONTANA.

TAG HOLDER.

Application filed March 2, 1923. Serial No. 622,399.

To all whom it may concern:

Be it known that I, CHARLES A. ROBERTS, a citizen of the United States, residing at Butte, in the county of Silver Bow and State 5 of Montana, have invented new and useful Improvements in Tag Holders, of which the following is a specification.

This invention relates to tags, and has particular application to a holder or fastener by 10 means of which the tag is prevented from being casually separated from the object to which it is attached.

More specifically stated, the tag holder forming the subject matter of the invention 15 is provided from a single length of material which is associated with the tag, and which terminates to provide a loop like terminal, the body portion of the holder being formed with a tongue and arranged to extend across 20 the loop in a manner to prevent the tag from being lost or otherwise casually separated from the object to which it is attached.

In the drawing forming part of this application, like numerals of reference indicate 25 similar parts in the several views, and wherein:

Figure 1 is a view in elevation of a tag equipped with a holder constructed in accordance with the invention.

Figure 2 is an edge elevation.

Figure 3 is a sectional view taken on the line 3—3 of Figure 1.

Figure 4 is a fragmentary view of a modified form.

Referring to the drawings in detail, 10 indicates a tag of well known construction, which is associated with the holder forming the subject matter of the invention.

This holder is formed from a single length 40 of any suitable material and indicated at 11. One end of the holder is provided with an opening to receive an eyelet 12 utilized to secure one end of the holder to the tag 10. The upper end of the holder 11 is bent upon 45 itself as at 13, and this portion is reversely bent inwardly as at 14 thus defining a loop like extremity to slip the holder on any support designed to accommodate the holder.

The body 11 of the holder is slit obliquely as 50 at 15 to provide a tongue or finger 16 which

is bent to extend diagonally across the loop at one side thereof. The tongue is sufficiently resilient to allow the holder to be slipped upon the support therefor, the support being received by the loop above defined, but 55 after the holder has been associated with the support, it is quite obvious that the particular arrangement or disposition of the tongue or finger 16 is such that the holder cannot become casually separated from its support. 60 The invention is very simple in construction and can be manufactured and sold at a nominal cost.

In Figure 4 I have shown a modified form of the holder, the latter being indicated at 65 11' and is provided with an opening 12' to accommodate an eyelet such as shown in Figures 2 and 3 for the purpose of associating the holder with the tag. However, this form of the invention varies from the preferred 70 form in that the holder 11' is formed with a plurality of bendable prongs 13' which surround the opening 12', so that the holder can be associated with the tag by means of said prongs in contra-distinction to the use of the 75 eyelet if so desired.

While it is believed that from the foregoing description, the nature and advantages of the invention will be readily apparent, I desire to have it understood that I do not 80 limit myself to what is herein shown and described and that such changes may be resorted to when desired as fall within the scope of what is claimed.

Having thus described the invention, I 85 claim:

A tag holder formed from a single piece of material having one end secured to the tag, the other end of said material being folded upon itself in a manner to provide an open loop, and a tongue or finger formed from the body of the holder and disposed at one side of the loop and diagonally disposed with relation thereto and adapted to engage the supporting means upon tendency 90 of the loop to become accidentally disengaged therefrom.

In testimony whereof I affix my signature.

CHARLES A. ROBERTS.
